(57) CLAIM

I claim the ornamental design for a child's garage-like playhouse with barn-type doors, as shown and described.

DESCRIPTION

FIG. 1 is a perspective view of a child's garage-like playhouse with barn-type doors showing my new design; FIG. 2 is a front elevational view thereof; FIG. 3 is a rear elevational view thereof; FIG. 4 is a left side elevational view thereof, the elevational view of the right side being a mirror image thereof; FIG. 5 is a top plan view thereof; and, FIG. 6 is a bottom plan view thereof.
